(57) **CLAIM**

The ornamental design for a electronic controller for a pump/motor unit, as shown and described.

DESCRIPTION

FIG. 1 is a bottom view of the invention;

FIG. 2 is a front view of the invention;

FIG. 3 is a left-side elevational view of the invention;

FIG. 4 is a perspective view of the invention;

FIG. 5 is a right-side elevational view of the invention;

FIG. 6 is a top view of the invention;

FIG. 7 is a bottom view of a second embodiment of the invention;

FIG. 8 is a front view of the second embodiment of the invention;

FIG. 9 is a left-side elevational view of the second embodiment of the invention;

FIG. 10 is a perspective view of the second embodiment of the invention;

FIG. 11 is a right-side elevational view of the second embodiment of the invention; and,

FIG. 12 is a top view of the second embodiment of the invention.

Structure in the drawing that is shown in broken lines is environmental and disclaimed.
